Nathaniel P. Richardson of Portland, Me.
Letters Patent No. 682. Dated Dec 12, 1854.

(See schedule referred to in these Letters Patent and making part of the same.)

To all Persons to whom these Presents shall come.

Be it known that I, Nathaniel Particular Richardson, of Portland, in the County of Cumberland and State of Maine, have invented, or produced a new or ornamental design for a Cooking Stove, which I term "the Banner" and which I do hereby declare is represented in the accompanying drawing, of which Figure 1. denotes a perspective elevation, —

Figure, 2, a horizontal section of its front plate taken — through the middle of its fire place door. — Figure, 3, is a vertical section of its side plate taken through the middle of each of the two smaller doors thereof. — Figure, 4, is a similar section of its side plate and its larger or oven door, the same being taken through the middle of the side door.

I would remark that in some respects this stove does

not materially differ from many others; it does however vary from them in its ornamental character or composition of its ornaments or mouldings. As by inspection of the drawing it will be seen that each of the doors as well as each side and front plate has arranged upon it and running around it a wreath or vine of grape leaves and grapes.

I do not intend to include in this design the ornamental character of the legs or feet of the stove, as these legs are not particularly unlike such as will be found in another design. The center panel of the main door of the side plate is formed with an ornament composed of scrolls, two flower desks and roses as represented in the drawing, and directly above this door, the side plate has an ornamental scroll branching in two directions over and about a rosette. Each of the panels of the smaller doors and the base mouldings are provided with ornaments as shown in Figure 1. The particular character of the ornaments on the main body of the stove, and the form or configuration of said body, and its mouldings for base and cornice will readily be comprehended by any skillful stove pattern maker on inspection and examination of the drawings herewith presented.

What I claim as my invention or production is the ornamental design of each of the doors and the side and front plates, the same being as exhibited in the drawings above mentioned.

In testimony whereof, I have hereunto set my signature this Twenty-second day of September A.D. 1854.
